(57) **CLAIM**

The ornamental design for a watch bracelet, as shown and described.

DESCRIPTION

FIG. 1 is a top view of a watch bracelet of my new design; FIG. 2 is a bottom view thereof; FIG. 3 is a right side view thereof; FIG. 4 is a left side view thereof; FIG. 5 is a front view thereof; FIG. 6 is a rear view thereof; and FIG. 7 is a top right perspective view thereof; FIG. 8 is a bottom left perspective view thereof; FIG. 9 is an enlarged top view portion of the watch bracelet shown in FIG. 1;

FIG. 10 is an enlarged right side view portion of the watch bracelet shown in FIG. 3;

FIG. 11 is an enlarged front view portion of the watch bracelet shown in FIG. 5; and,

FIG. 12 is an enlarged top right perspective view portion of the watch bracelet shown in FIG. 7.

The dot-dash broken lines represent the designation of enlargement views and form no part of the claimed design.

1 Claim, 12 Drawing Sheets
